W. S. ADAMS.

JOURNAL BOX LID.

APPLICATION FILED FEB. 14, 1917.

1,240,002.

Patented Sept. 11, 1917.

UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

JOURNAL-BOX LID.

1,240,002.

Specification of Letters Patent. Patented Sept. 11, 1917.

Application filed February 14, 1917. Serial No. 148,509.

To all whom it may concern:

Be it known that I, WALTER S. ADAMS, a citizen of the United States, residing in Philadelphia, Pennsylvania, have invented 5 certain Improvements in Journal-Box Lids, of which the following is a specification.

My invention relates to certain improvements in lids for journal boxes for car axles.

10 One object of my invention is to provide a lid which can be readily opened and closed and which will remain in either position.

A further object of the invention is to make the lid absolutely water tight when in 15 the closed position. The invention also relates to details of construction which will be fully described hereinafter.

In the accompanying drawings:

Figure 1 is a front view of a journal box 20 illustrating my improved lid;

Fig. 2 is a sectional view on the line 2—2, Fig. 1, showing the lid closed;

Fig. 3 is a similar view showing the lid 25 opened; and Fig. 4 is a perspective view showing the spring bearing plate.

Referring to the drawings, 1 is the body of the journal box made in the usual manner. 2 is the turned up lip at the lower portion of the box. 3 is a lug to which the lid 4 is pivoted by the usual pivot pin 5. The lug is shaped as shown in Figs. 2 and 3 and has a flat surface 3^a and a rounded surface 3^b. Directly under the lug is a shoulder 6, which extends the same distance as the sides 7, so

35 that when the lid is in the closed position, as in Figs. 1 and 2, the inner portion 7^a of the lid will rest tightly against the shoulder 6, upturned lip 2 and the sides 7, excluding water or dust. On the lid 4 is an enlargement

40 forming a recess 9 in which is mounted the spring bearing plate 10, the upper edge of which bears against the lug 3, the lower edge being bent in the form of a socket 11 to fit over a lug 12 projecting into the

45 space 9 of the portion 8 of the lid. A coiled spring 13 rests in a pocket 14 in the enlargement 8 and against the spring bearing plate 10 and acts to hold the lid firmly against the box when the lid is closed, as illustrated in

50 Fig. 2. When the lid is raised to the open position, as in Fig. 3, the spring tends to hold the lid in this position, but when the lid is turned down to a position approximately one-third closed the spring will snap 55 the lid into the closed position. The en-

largement 8 has a hood 15 which extends over the lug 3 so as to prevent the entrance of water into the space 9 in the lid, but, in the event of water passing into this space, I provide a drip opening 16 at the bottom of 60 the space, as shown in Figs. 1 and 2, and this drip opening carries the water to the outside of the lid and away from the box.

By this means, I provide a very simple and effective lid, which can be easily moved 65 into the open or the closed position, and which will be rigidly held in either position.

By providing the box with a continuous flat surface formed by the ends of the side members 7, the shoulder 6 and the projecting 70 portion 2, dust and moisture are excluded, the portion 7^a sealing the box when the lid is closed.

I claim:

1. The combination of a journal box having a continuous bearing surface at the forward end; a lug at the upper portion of the box having a rounded surface and a flat surface; a lid pivoted to the lug and having an inner portion of such a size as to rest against 80 the bearing surface of the box, said lid having an enlargement inclosing a space; a lug on the inner portion of the lid extending into the space; a spring plate mounted on the lug and bearing against the pivot lug on 85 the box; and a spring between the outer wall of the lid and the plate.

2. The combination of a journal box having a continuous bearing surface at the forward end; a pivot lug at the upper end of the 90 box; a lid pivoted to the lug and having an inner portion arranged to fit against the continuous bearing surface; an enlargement on the lid extending over the pivot and having a pocket near a point opposite the pivot 95 of the lid; a spring bearing plate resting against the inner portion of the lid and the lug and a coiled spring located in the pocket and bearing against the plate, the lug having a rounded portion on which the bearing 100 plate travels when moved from the open to the closed position; the enlargement of the lid having a drip opening to allow any water, which gains access to the interior of the lid, to escape outside of the box.

3. The combination of a journal box having a continuous surface at the forward end; a projecting pivot lug having a flat surface and a rounded surface; a lid pivoted to the lug, said lid being made in one piece and 110

having an inner portion bearing against the continuous bearing surface and an enlargement on the outside of the lid forming a space; a lug projecting from the inner portion of the lid into the space; a bearing plate having a curved socket fitting the lug and bearing against the pivot lug of the box; a spring located between the bearing plate and

the extension on the lid, the extension having a hood projecting over the pivot lug on the ¹⁰ box; said bearing plate being so arranged as to travel on the curved portion of the pivot lug.

In witness whereof I affix my signature.

WALTER S. ADAMS.
